ATTORNEYS.

UNITED STATES PATENT OFFICE.

WILLIE B. MUNGER, OF HARRISBURG, PENNSYLVANIA.

DESIGN FOR A BADGE.

SPECIFICATION forming part of Design No. 21,846, dated September 6, 1892.

Application filed August 9, 1892. Serial No. 442,622. Term of patent 3½ years.

To all whom it may concern:

Be it known that I, WILLIE B. MUNGER, a citizen of the United States, residing at Harrisburg, in the county of Dauphin, and State of Pennsylvania, have invented and produced a new and original design for Badges, of which the following is a specification.

Reference is to be had to the accompanying drawing, forming a part of this specification, in which the figure represents a face view of a badge embodying my new design.

The leading feature of my design consists of the surface ornamentation of the main portion or body of the badge. Thus *a* indicates

a representation of the globe, and *b* a circular series of women's heads surrounding the globe, the ornamentation thus forming a rebus enigmatically expressing "World's Fair."

The minor features of the design are a displayed eagle *c*, surmounting the body of the badge, and the circular form of the latter.

I claim—

The design for a badge herein shown and described.

WILLIE B. MUNGER.
